UNITED STATES PATENT OFFICE.

RAYMOND D. SMITH, OF ARLINGTON, MASSACHUSETTS, ASSIGNOR TO TREMONT PRODUCTS COMPANY, OF BOSTON, MASSACHUSETTS, A CORPORATION OF MASSACHUSETTS.

HEAT-DISSIPATING SOCKET-SWITCH.

1,343,690.

Specification of Letters Patent. Patented June 15, 1920.

Application filed June 5, 1917, Serial No. 172,932. Renewed August 12, 1919. Serial No. 317,099.

To all whom it may concern:

Be it known that I, RAYMOND D. SMITH, a citizen of the United States, residing at Arlington, in the county of Middlesex and 5 Commonwealth of Massachusetts, have invented certain new and useful Improvements in Heat-Dissipating Socket-Switches, of which the following is a specification.

This invention relates to improvements in 10 the construction of socket-switches which are subject to heat generated by the electric current, and particularly to lamp-dimming socket-switches of a type disclosed in my copending application, Serial No. 141,676.

15 In such type of incandescent lamp socket-switch, which incorporates in compact form an auxiliary, self-contained, electrical resistance as a means for reducing the current through the lamp to dim the latter, it develops in practice that the heat necessarily 20 generated in this resistance must be suitably dissipated to prevent the excessive accumulation thereof in the switch structure and in the base of the incandescent lamp. If not 25 sufficiently dissipated, this heat may raise the temperature of the socket-switch structure and of the lamp to such a degree as to cause serious impairment. Thus, surface 30 corrosion of the switch contacts and deterioration of the switch-insulating fiber parts may be caused in the one case, and melting or softening of the soldered lamp-base connections and of the bulb-holding cement, in the other.

35 Accordingly, the general object of the present invention is to provide a lamp-dimming socket-switch possessing all the advantageous features of the socket-switch disclosed in my said copending application, but 40 wherein the resistance unit and the associated socket and casing parts are so relatively arranged and formed that the heat generated in the former is rapidly dissipated to the atmosphere, thus preventing the 45 accumulation thereof in the metallic parts of the socket and in the lamp base and avoiding thereby the consequent evil effects above described.

50 My present invention particularly contemplates the accomplishment of the above object by so positionally relieving the resistance unit and the juxtaposed socket parts each from the other, and by so piercing these several parts, that free air has vent 55 theretwixen and therethrough, thus pre-

venting the excessive accumulation of heat, and so that direct heat conduction from the resistance unit to other parts is retarded.

A further and important object of the invention is to provide such ventilation as 60 above described by an arrangement of parts whereby the substantial dimensions and form, and also the features of insulation and assemblage of the usual chain-pull socket-switch, in all their efficient details as at 65 present developed and well known in the art, shall be fully preserved. The term assemblage, as here used, is meant to include the method of telescopic attachment of the outer socket casing and its supporting metallic cap, whereby in a readily detachable manner these two parts are securely locked together for supporting the socket as a whole; and also is meant to include the usual manner in which the socket-switch is inserted and held within this outer casing, so that no new problem of wiring or of assemblage shall confront the electrician when installing this fixture, or permanent type of 75 my improved socket-switch.

A still further object is to provide a shade holder of suitable size and form and of agreeable appearance, itself coöperatively perforated and conformed with the outer casing of the socket-switch to be supported 80 thereby and to aid in the dissipation of heat by providing additional conductive and radiative agencies.

Novel details of arrangement and construction by which the above mentioned objects, among others, are effectively accomplished, include an arrangement of relatively spaced flanges (preferably two on the threaded lamp receptacle and two on the resistance-supporting drum), so that metallic 90 contact between these parts (both of which are supported by a common insulating block) is avoided; the provision of a generously ventilated air space, of appreciable volume, between the threaded lamp receptacle and the said metallic resistance drum, and of a similar ventilated air space between 95 said drum and the outer supporting casing; the relieved lower surface of the lower insulating block, whereby free access and circulation of air for cooling purposes is further afforded; and the relative diametrical dimensions of the switch body and casing in their different parts, whereby the latter telescopically may receive the former, "lamp-re- 100 105 110

ceptacle first," as is customary in socket-switches, and desirable for certain purposes of assemblage, and whereby the socket body may be axially supported and laterally guided preferably by engagement of the lower extremity of the resistance drum with the inturned lower extremity of the outer casing.

Other improved features of construction will be pointed out in the following description wherein reference is had to the accompanying drawings in which—

Figure 1 is a view of my improved lamp-dimming socket-switch, the same being shown partially in section on a central, vertical plane and with the casing and resistance unit partially broken away more clearly to show the interior construction; Fig. 2 is a view taken partially in section and looking downwardly on the plane 2—2 in Fig. 1, the upper switch actuating parts being omitted for clearness; Fig. 3 is a section on the plane 3—3 in Fig. 2 showing a detail of construction; Fig. 4 is an exploded view showing in perspective the lower insulating block and the lamp receptacle and resistance unit supported therebelow; Fig. 5 is a diagram of electrical connection; Fig. 6 is a fragmentary view showing a modification in form and construction of the outer casing and shade holder; Fig. 7 shows a desirable way in which ventilation may be provided for the switch chamber; Fig. 8 is a fragmentary view of the perforated insulating block used with the construction shown in Fig. 7; and Fig. 9 shows partially broken away and partially in section, a modified or "adapter" type of my improved dimming-socket.

Throughout the drawings identical parts are designated by similar reference numerals.

In Figs. 1 to 4, inclusive, the usual upper and lower switch-insulating blocks appear at 45 and 11 respectively, supporting therebetween the switch mechanism, which in the preferred embodiment herein disclosed, comprises a type of ratchet-driven or pull-switch well known in the art and includes an oscillatory driving wheel 12, a flexible pull chain 13, the operating spring 14 and the ratchet-driven, contact-bridging plate 15, having spring wiper arms 16, 16 adapted electrically to connect diametrically opposite pairs of 55 stationary contact leaves 17, 18, and 19, 20, which occupy selected members of a circular series of inclines formed on the upper surface of the lower insulating block 11.

Current supply leads 25 and 26, the lamp 60 27, and a resistance winding 28, hereinafter to be described in detail, are electrically interconnected, together with the said contact leaves, in a manner easily understood from reference to Fig. 5.

The coöperating ratchet arrangement for

rotatively driving the plate 15 in the direction of the arrow in Fig. 2 is such that, starting from the position of this plate as shown in said figure, where said plate bridges contact leaves 17 and 18 and thereby supplies full current directly to the lamp, a full stroke upon the chain 13 will rotate the wiper arms of this contact plate substantially a quarter-turn and to a position for bridging the blank inclines 21, 21 in which position all current through the socket is broken; and the said ratchet arrangement is further such that a partial stroke may rotate the plate 15 only sufficiently to permit the latter to drop to a seat on the contact leaves 19, 20, in which position, current to the lamp must pass through the resistance winding 28, thus reducing such current and dimming the lamp. An optional sequence of current control is thus available, dependent on whether a full or partial stroke is imparted to the pull chain, and the lamp consequently may either be extinguished or dimmed at will and by a single stroke on the chain when the lamp is burning at full brilliancy.

The improvement with which the present invention is most concerned, resides, as hereinbefore stated, in the novel structural arrangement of the resistance winding 28, and of the associated socket and casing parts. 95 This winding comprises a single layer of fine resistance wire 28 wound helically upon a metallic drum 30 and insulated therefrom by an interposed layer 31 of some suitable refractory material, such as mica. Another 100 insulating and protecting layer 32 of material having similar refractory quality, such as asbestos tape, is then applied to cover the winding 28 and is secured by some suitable adhesive, such as sodium silicate.

The drum 30 at its upper edge carries two inwardly extending flanges 33 and 34 which are secured to the lower surface of the block 11 by screws 35 and 36 for supporting said drum. The holes in the flanges 33 and 34 110 for said screws are each provided with a bushing 37 as shown in Fig. 3, for both electrically and thermally insulating the drum 30 from said screws and metallic parts contacted by the latter.

In its upper portion, the drum 30 and the layers wound thereon are perforated by a series of vent holes 38, to provide escape for the heated air contained in the space 40 between the said drum 30 and the threaded lamp receptacle 41. Foil strips 22 and 23 connect the extremities of the resistance winding 28 with contact leaves 17 and 19 respectively as shown in Figs. 1 and 4—the strip 23 being suitably insulated where it 125 crosses said winding, by a strip of mica or asbestos paper 24, and both strips being suitably secured to avoid contact thereof with other than the designed metallic parts.

The lamp receptacle 41 is secured also to 130

the insulating block 11 by means of flanges 42, 43 and screws 44, 45 in a manner similar to that in which the drum 30 is held; it being noted that the said latter flanges are so arranged and spaced, relative to those of said drum, that no metallic contact exists between the said drum and the lamp receptacle in any parts thereof, and that thus direct conductance of heat from the former to the latter is prevented.

Surrounding the switch mechanism and its supporting blocks 10 and 11 is a split, removable insulating sleeve 50, of some flexible material, such as pressed fiber, the outer diameter of which sleeve is as large or larger than the outer diameter of the resistance winding 28. An outer shell 51, at an upper portion thereof, is adapted snugly to encompass the said sleeve and to be telescopically slidable relative thereto, and at another and lower portion, said shell is relatively enlarged or swollen, thereby to be relieved from close proximity to the heat generating resistance winding 28, but tapering at the extreme bottom portion to a smaller diameter and further termination thereof in a narrow in-turned flange 52, which bottom portion thereby provides a firm axial support for the socket-switch body by presenting a seat and lateral guiding wall for the lower edge of the resistance carrying drum 30.

In simple socket-switch structures, it has heretofore been common to support the inner switch body by engagement of the outer and lower edge of the lower insulating block thereof with a shoulder formed by a decrease in diameter of the outer inclosing shell in a lower portion thereof. The novel method of support which I have above described, however, renders possible a firmer holding of said switch body within the inclosing shell, because less telescoping surface is presented and less looseness is therefore required in the fit of the inclosing shell about said body; at the same time, although retaining the exact nature of telescoping assemblage common to socket-switches in general, I obtain the above advantage, together with a generous spacing of said outer shell from said resistance sleeve in the portion of the former proximate the latter.

To further the free access of air into and around the space inclosed by the resistance winding 28 and the outer shell, I preferably perforate the latter with large and numerous openings, or, if desired, I may construct this shell with substantially an unobstructed annular and upward opening approximately at a height of the lower insulating block 11 as shown in Fig. 6, through which the heat and air drafts may freely rise to escape confinement by the portions of the shell surrounding said resistance winding.

In either form of the outer casing, a shell formation is presented available for supporting a suitable shade-holder, such as appears at 53, for supporting an outer shade 49, said shade-holder in either case being in its upper portion conformed to the shape of the shell 51 to an extent whereby appreciable area of metallic contact is presented for conducting away and radiating the heat from said shell.

In Figs. 7 and 8, I have shown further provision for facilitating the escapement of heat, particularly from the switch chamber. Here numerous shielded openings 54 are formed by striking outwardly the metal in 70 the walls of the outer shell 51, and similar treatment may be accorded the cap 55 as shown at 56. Said cap may have the usual telescoping and locking engagement with the upper portion of the outer shell, the ventilation being furthered by the provision of air passages 57 through the upper insulating block 10. In this construction the insulating sleeve 50 is, of course, correspondingly perforated at 58, and likewise any 80 lining contained in the cap. In Fig. 7 also, inter-communicating recesses 59 are shown in the lower surface of the block 11, through which air may circulate for cooling the heretofore described supporting flanges of the 85 lamp receptacle and resistance drum.

Fig. 9 illustrates a modified form of my improved socket-switch above described, wherein the cap 55 is dispensed with, and the upper insulating block 10 is increased 100 in size and provided with insulated brackets 60 to which the shell 51 may be secured by lateral screws 61. A threaded plug 62, of standard lamp-base dimension replaces the supply lead 25 and a center contact tongue 105 63, the supply lead 26; so that proper electrical connection is had by inserting this "adapter" type of socket-switch in an ordinary lamp socket. Ventilation for cooling the switch chamber is afforded by the 110 openings 64 in the porcelain block 10.

The novel features of construction which in a socket-switch structure I have provided, as herein described, for aiding in the dissipation of heat and for preventing the undesirable accumulation thereof within the switch or lamp supporting elements, are obviously available for use with any socket wherewith is incorporated a heat-generating electrical unit whether such unit be the incandescent lamp itself, or otherwise, as in the present case; and wherein it is desired to retain the advantages of the usual principles of shell assemblage and support; and my invention is therefore not limited to the 115 precise embodiment thereof herein disclosed, but what I claim as new is:

1. The combination with a socket-switch structure, including a lower supporting and insulating block for a switch mechanism 120

carried thereabove, and a lamp receptacle depending from the lower surface of said block; of an insulated supporting drum rigidly secured to the lower face of said block, surrounding said receptacle and spaced therefrom at all points; an insulated resistance winding carried by said drum; an outer supporting and protecting casing adapted telescopically to receive and to inclose both said socket-switch structure and said resistance winding,—said casing having an inwardly extending lower portion adapted to support the said drum and thereby said socket-switch structure by engagement with the former; together with means of attachment for said casing whereby said socket-switch structure is retained therewithin.

2. The combination with a socket-switch structure, including a lower supporting and insulating block for a switch mechanism carried thereabove, and a lamp receptacle depending from the lower surface of said block; of an insulated supporting drum rigidly secured to the lower face of said block, surrounding said receptacle and spaced therefrom at all points; an insulated resistance winding carried by said drum, said drum being perforated at the upper portions thereof to give air-vent to the space between said receptacle and said drum; an outer supporting and protecting casing adapted telescopically to receive and to inclose both said socket-switch structure and said resistance winding,—said casing having an inwardly extending lower portion adapted to support the said drum and thereby said socket-switch structure by engagement with the former; together with means of attachment for said casing whereby said socket-switch structure is retained therewithin.

3. The combination with a socket-switch structure, including a lower supporting and insulating block for a switch mechanism carried thereabove, and a lamp receptacle depending from the lower surface of said block, of an insulated drum rigidly secured to the lower face of said block, surrounding said receptacle and spaced therefrom at all points; an insulated resistance winding carried by said drum; an outer supporting and protecting casing adapted telescopically to receive and to inclose both said socket-switch structure and said resistance winding,—said casing being relatively enlarged and perforated in a portion thereof proximate the said resistance winding to provide a well ventilated air space between said portion and said winding, and the said casing being further relatively decreased in size at its lower portion and thereat formed to support the said drum and said switch structure by engagement with the lower extremity of the former; to-

gether with means of attachment for said casing whereby said socket-switch structure is retained therewithin.

4. The combination with a socket-switch structure, including a lower supporting and insulating block for a switch mechanism carried thereabove, and a lamp receptacle depending from the lower surface of said block, of an insulated supporting drum rigidly secured to the lower face of said block, surrounding said receptacle and spaced therefrom at all points; an insulated resistance winding carried by said drum, said drum being perforated at the upper portions thereof to give air-vent to the space between said receptacle and said drum; an outer supporting and protecting casing adapted telescopically to receive and to inclose both said socket-switch structure and said resistance winding,—said casing having an inwardly extending lower portion adapted to support the said drum and thereby said socket-switch structure by engagement with the lower extremity of the former; together with means of attachment for said casing whereby said socket-switch structure is retained therewithin.

5. The combination with a cylindrical socket-switch structure, including a lower insulating button for supporting a switch mechanism carried thereabove; of a cylindrical and removable insulating wall inclosing the said mechanism; a lamp receptacle depending from the lower surface of said button; an insulated and rigidly mounted resistance unit formed as a cylindrical sleeve, surrounding the said receptacle and spaced therefrom at all points, said unit having an internal diameter substantially greater than the outer diameter of said receptacle, and an outer diameter not greater than the outer diameter of said wall; and an outer, cylindrical inclosing casing for said structure and said unit telescopically removable therefrom, said casing having in its upper portion an inner diameter not less than the outer diameter of said wall, and having at its lower portion a relatively less diameter for engaging with said resistance unit axially to support the same; together with means of attachment for said casing whereby said socket-switch structure and resistance unit are retained therewithin.

6. A socket-switch structure, embodying in combination; an upper and lower insulating block with switch mechanism supported therebetween; a lamp receptacle depending from the lower surface of said lower block; a resistance carrying sleeve rigidly mounted on said lower block surrounding said re-

- ceptacle and spaced therefrom at all points; an outer inclosing shell adapted at the upper or larger end thereof telescopically to receive first said sleeve and then said blocks 5 and near the lower or smaller end axially to support the same by engagement with said sleeve; and a cap formed to lock with said upper end of said shell, to hold said blocks and said sleeve therewithin.
- 10 7. A socket-switch structure, embodying in combination; an upper and a lower insulating block with switch mechanism supported therebetween; a lamp receptacle depending from the lower surface of said lower block; a resistance carrying sleeve rigidly mounted on said lower block surrounding said receptacle and spaced therefrom at all points, said resistance sleeve being perforated to give vent to the space between same and 15 said receptacle; an outer inclosing shell adapted at the upper or larger end thereof telescopically to receive first said sleeve and then said blocks and at the lower or smaller end axially to support the same by engagement 20 with said sleeve, the said shell being relatively enlarged in a lower portion thereof to provide a space between said lower portion and said sleeve, and said shell also having openings in said portion to provide 25 air vent for said space; and a cap formed to lock with said upper end of said shell, to hold said blocks and said sleeve therewithin.
8. A socket-switch structure, embodying in combination; an upper and a lower insulating block with switch mechanism supported therebetween; a lamp receptacle depending from the lower surface of said lower block; a resistance carrying sleeve rigidly mounted on said lower block surrounding 30 said receptacle and spaced therefrom at all points; an outer inclosing shell adapted at the upper or larger end thereof telescopically to receive first said sleeve and then said blocks and switch mechanism, and adapted at a lower portion to support the 35 same; the said shell having openings in a portion thereof opposite said switch mechanism, to give air vent to the space containing the latter; and a cap formed to lock with 40 said upper end of said shell, to hold said blocks and said sleeve therewithin, the said cap also having air vents therethrough; together with perforations in the said upper insulating block whereby free communication 45 of the air in the spaces above and below said upper insulating block is established.
- 50 9. In a socket-switch structure, in combination; a lower insulating and switch-supporting block; two stationary and con-
- centrically disposed shells having separate and spaced flanges whereby said shells are rigidly and independently mounted on the lower surface of said block, the said shells being of relatively different diameters 55 whereby a substantial air space is provided therebetween, the inner of said shells being adapted to receive the base of an incandescent lamp, and the outer of said shells carrying a heat generating resistance unit operably connected to the switch.
- 10 10. In a socket-switch structure, in combination; a lower insulating and switch-supporting block; two stationary and concentrically disposed shells having separate and spaced flanges whereby said shells are rigidly and independently mounted on the lower surface of said block, the said shells being of relatively different diameters 60 whereby a substantial air space is provided therebetween, and the inner of said shells being adapted to receive the base of an incandescent lamp; a resistance winding and insulating layers therefor carried externally on the outer of said shells, said winding 65 having operative electrical connections with the socket switch; and an outer inclosing and supporting casing formed at one end thereof telescopically to receive the said shells and said supporting block, and at the 70 other or smaller end axially to support and laterally to guide the same by engagement with said outer shell.
11. In a socket switch structure, the combination of an insulating plate carrying 75 switch mechanism thereabove; a cylindrical lamp receptacle attached to the lower surface of said plate; a stationary and rigid sleeve, carrying a resistance, and attached to the structure surrounding and spaced 80 from the said receptacle; and a cylindrical casing formed to telescope with the conjoined switch-plate-and-sleeve structure, and further formed to support the same; together 85 with means to lock said conjoined structure 90 within said casing.
12. A structure as specified in claim 1, in which the lower surface of the insulating block, therein recited, is provided with recesses communicating with each other and 95 with the spaces between said receptacle, drum, and casing, whereby air circulation between and around these parts is facilitated to aid in the dissipation of heat.
- Signed at Boston, Massachusetts, this 4th 110 day of June, 1917.
